(57) **CLAIM**

The ornamental design for a body composition analyzer, as shown and described.

DESCRIPTION

FIG. 1 is a front, top, and right side perspective view of a body composition analyzer according to the new design; FIG. 2 is a front elevational view of the body composition analyzer of FIG. 1; FIG. 3 is a rear elevational view of the body composition analyzer of FIG. 1; FIG. 4 is a left side elevational view of the body composition analyzer of FIG. 1; FIG. 5 is a right side elevational view of the body composition analyzer of FIG. 1; FIG. 6 is a top plan view of the body composition analyzer of FIG. 1; and, FIG. 7 is a bottom plan view of the body composition analyzer of FIG. 1. The broken lines are included for the purpose of illustrating portions of the body composition analyzer that form no part of the claimed design.
